UNITED STATES PATENT OFFICE.

HJALMAR CARLSON, OF DULUTH, MINNESOTA.

JACK.

Application filed December 10, 1926. Serial No. 153,864.

This invention relates to jacks and has special reference to a collapsible automobile jack that may be used either as an elevating frog upon which the automobile may be run, or as an ordinary jack.

The principal object is to provide a simple and efficient device of this character especially adapted for use as a frog upon which the automobile may be run by its own power.

Another object is to provide such a device that may be conveniently folded for transportation.

Still other objects and advantages of the invention will appear in the further description thereof.

Referring now to the accompanying drawing, forming part of this application, wherein like reference characters indicate like parts:

Figure 1 is a semi-sectional view showing the centermost jacking elements in elevation;

Figure 2 is a top plan view of the completely assembled jack or frog, except that the uppermost covering plate of the jacking members is removed;

Figure 3 is a combined enlarged section and elevation taken on the line 3—3 Figure 1, also having the covering plate removed; and

Figure 4 is an enlarged perspective view of the innermost end of one of the body portions of the jack.

The body portion of the jack comprises the two flat metal members 1 and 2, separately united as at 3, so as to permit of being knocked down for transportation purposes when desired. These members are each provided, longitudinally of their centermost portions, with spaced Z-bars 4 securely attached thereto, forming channels as is obvious in which the spaced rollers 5 may reciprocate in their travel longitudinally of the upper faces of the members 1 and 2. These rollers carry upon their supporting shafts, those on the member 1, the arcuately shaped jacking member 6, and those on the member 2, the similar arcuately shaped member 7; those supporting the member 6 being spaced somewhat farther apart than those supporting the member 7, for reasons which will subsequently appear. These two members 6 and 7 are pivotally united upon the shaft 8 so that as their lower ends, supported on the rollers as previously de-

scribed, are drawn toward each other, or separated, the pivotal connection 8 may function. I prefer to have the ends of the members 6 and 7, adjacent the pivotal connection 8 each provided with an arcuately shaped protruding prong 9, so that when the supporting ends of these members are drawn more closely together, as indicated in dotted lines in Figure 1, said prongs will provide a varying saddle or seat for the object supported, for example, the axle of a car, when the device is being used as a common jack, the object of which is obvious. To the sides of the lower widened end of the member 6 are mounted two spaced upright bracket-like members 9, intermediate of which is mounted upon the shaft 10 the small drum 11 having formed integral therewith at one end the ratchet wheel 12. Normally engageable with this ratchet wheel 12 is the pawl 13 held in such engagement by a suitable spring 14, and the handle 15 of the pawl is widened considerably to provide convenient engagement by the operator's foot when it is desired to release the jack by disengaging the pawl from the ratchet wheel.

The shaft 10 protrudes beyond the bracket 9 on one side of the member 6 and carries thereupon a common ratchet wrench, indicated at 16, by the depression of which the shaft 10 is rotated intermittently in a clockwise direction as viewed from the opposite end. About the drum 11 is wound a line 17 which passes over the drum, downwardly of the inner side thereof and beneath the small sheave 18, carried by the member 6, and thence suitably attached as at 19 adjacent the rollers 5, which support the lower end 90 of the member 7. This line is for the purpose of drawing the lowermost supporting ends of the members 6 and 7 together when the shaft and drum are rotated, and it is evident that the line will function as holding means for the lower ends of the members in any desired spaced position as long as the pawl 13 properly engages the ratchet wheel 12, and that by pressing downwardly on the handle end of the pawl 13 it will be 105 disengaged from the ratchet 12 and allow the lower ends of the members 6 and 7 to separate, thus lowering their pivotal connection 8.

As auxiliary supporting means for the 110 jack I provide a pair of members similar in shape, size and connection to the members

6 and 7, upon either side thereof, and spaced therefrom, as clearly indicated in Figures 2 and 3 of the drawings, these members being illustrated at 20. The shaft 8, it will be noted, which forms the pivotal connection to the members 6 and 7, extends laterally from both sides thereof and also forms the pivotal connection for the pairs of the members 20, and the lower ends of these members simply drag back and forth upon the upper faces of the members 1 and 2 to help support the members 6 and 7. Flanges 21 are provided upon the members 1 and 2 externally of the pairs of members 20 to act as guides therefor, and outboard of one of these flanges I have shown an extension 22 of the edges of the members 1 and 2 to provide a step for the supporting member 23, which, as indicated at 24, is provided with a head strap or yoke for convenient engagement with the hub of a wheel that is to be run up onto the frog so that the member 23, being of the proper length, will drag itself along on the extension 22 of the jack, and when the wheel is fully raised on the members 6 and 7, the member 23 will be substantially vertical under the axle. When the frog is depressed or collapsed this member 23 will act as a support for the axle of the car, or, as is obvious, any other form of support in the form of blocks or the like may be put under the wheel or axle of the car before the frog is collapsed; and, all that is necessary to accomplish the latter is to press downwardly on the handle 15 of the dog 13 after removal of the ratchet wrench 16, when the frog may be entirely removed if desired. At the supporting end of the jacking members 7 I provide a small toe board 27 pivotally mounted upon the axle of the rollers 5 in any desired manner to lessen the abruptness of the approach for a wheel mounting the jack and also for the purpose of preventing the jacking members from being slid to the extreme operating end of their supporting members, as might occur from the mounting of the car upon the jack, as the toe board overlaps the extreme outer end of the member 2.

The pivotal connection of the members 1 and 2, which is indicated at 3 in Figure 1, is preferably accomplished by the slightly bent prongs 28 carried by and protruding over the end of the member 1 for holding engagement with suitable eyes indicated at 29 extending upwardly from the face of the member 2 adjacent the extreme inner end thereof so that when the outermost ends of the members 1 and 2 are raised they may be conveniently hooked or unhooked, and yet when thus united the ends prevented from being forced downwardly and their abutting edges humped as might occur when the jack is used upon soft ground.

The covering plate for the jacking mem-

bers previously referred to is illustrated at 25, it having suitable openings indicated at 26 through which the extreme ends 0 of the members 6 and 7 may protrude when the latter are abnormally elevated, as indicated in dotted lines, Figure 1. This covering plate is preferably of metal and securely riveted to both the members 6 and 7 and both pairs of similar members 20 so that it becomes a rigid portion of the jacking element and may further be covered by cushioning means such as rubber or the like, not shown, for convenience in the mounting of the automobile wheel.

Having thus described my invention, what I claim and desire to secure by Letters Patent, is

1. A device of the character described comprising a flat, rectangularly-shaped body portion, pivotally united members normally lying prone upon and cooperatively connected with said body portion, the remote ends of said members being slidable upon their respective body portions, and means carried upon the slidable end of one of the members and connected with the other whereby they may be pivotally operated.

2. A device of the character described comprising a body portion composed of two ground engaging supporting members, separable cooperative means upon the abutting ends of said members for pivotally uniting same, pivotally united members mounted upon the ground engaging members, one of said pivotal members carrying operating means and slidable upon its supporting member.

3. A device of the character described comprising two separable supporting members, pivotally united members the remote ends of which are mounted one upon each of the supporting members and one of said pivotal members being made slidable upon its supporting member, a pawl controlled winding drum carried upon the slidable member, a line operated by the drum connecting the remote ends of the pivotal members for raising and lowering said members.

4. A device of the character described comprising a two-part, foldable body portion, pivotally united members normally lying prone upon and cooperatively connected with said body portion, and means carried by one of the members and connected with each other whereby they may be pivotally operated.

5. A jack of the character described comprising two pivotally united members, operating means carried wholly by one of said members and connected to the other member whereby they may be pivotally operated.

In testimony whereof I affix my signature.

HJALMAR CARLSON.
